Attorney

UNITED STATES PATENT OFFICE.

EUGENE BERNINGHAUS, OF CINCINNATI, OHIO, ASSIGNOR TO THE EUGENE BERNINGHAUS COMPANY, OF CINCINNATI, OHIO, A CORPORATION OF OHIO.

SURGICAL AND DENTAL CHAIR.

Application filed September 16, 1921. Serial No. 501,170.

To all whom it may concern:

Be it known that I, EUGENE BERNINGHAUS, a citizen of the United States, residing at Cincinnati, in the county of Hamilton and State of Ohio, have invented certain new and useful Improvements in Surgical and Dental Chairs, of which the following is a specification.

My invention relates to improvements in surgical or dental chairs. One of its objects is to provide an improved surgical chair having a variety of adjustments adapting it to be used for a large variety of examinations and minor operations. Another object is to provide an improved chair back and means for mounting and adjusting the same. Another object is to provide for a releasable connection between the arms and foot board and the back whereby the back may be adjusted to a horizontal or nearly horizontal position without corresponding movement of the arms and foot board. Another object is to provide for a substantially horizontal position of the back in a substantial plane with the chair seat, and a foot board member also adjustable into a substantially horizontal plane with the face of the seat and back. Another object is to provide improved means to hold the back adjusting means in either released position or in automatic gripping position. My invention also comprises certain details of form, combination and arrangement, all of which will be fully set forth in the description of the accompanying drawings, in which;

Fig. 1 is a perspective view of a surgical chair embodying my improvements.

Fig. 2, is a side elevation of a portion of the chair shown in Fig. 1, and in a different position of adjustment.

Fig. 3, is a horizontal sectional detail partly in section on line 3-3 of Fig. 2.

Fig. 4, is a perspective view of the locking hand wheel detached.

Fig. 5, is a perspective view of one of the detachable links detached.

Fig. 6, is a perspective view of one of the back supporting brackets detached.

Fig. 7, is a perspective view of a releasing dog detached.

Fig. 8, is a plan view of the head rest and shoulder stays detached.

The accompanying drawings illustrate the preferred embodiment of my invention in

which 14 represents the base, 15 represents a plunger or standard seated in a cylinder located in the base and hydraulically and vertically adjustable relative to said base through the operation of a hand lever 16.

The hand lever 16 also preferably has a position of adjustment at which the plunger is rigidly locked to the base against movement either vertically or rotatably, thereby providing for adjusting the plunger either vertically or rotatably to secure a convenient position and suitable illumination of the chair and then locking the plunger rigidly to its adjusted position.

A chair seat frame 17 provided with an upholstered seat 18 is rigidly mounted upon the plunger 15. The seat frame is provided with upwardly projecting forward brackets 19 and rearward brackets 20. A foot rest frame 21 provided with a foot rest 22, and also preferably with an adjustable and detachable auxiliary foot rest 24, is pivotally attached to and suspended from the forward brackets 19. A chair back 25 is provided with side brackets 26 the projecting ends of which are pivotally attached to the free ends of the rearward brackets 20, so that the chair back has a range of adjustment of more than ninety degrees upon said rearward brackets, that is from a substantially horizontal or slightly inclined position where it is substantially in the same plane with the seat to a substantially vertical position at nearly right angles to the seat.

A pair of chair arms 27 and 28 are respectively pivotally attached at their forward ends at 30 to the upper ends of the side bars 29 of the foot rest frame 21. At the rear ends the arms 27 and 28 are respectively pivotally attached to the free ends of the rearward arms 20 by means of links 31. Thus as the foot rest frame 21 is rocked upon its pivotal connections with the brackets 19 the arms 27 and 28 are also rocked endwise due to their pivotal connection with the arms 29 of the foot rest frame 21. As illustrated in Fig. 1 the back is not directly connected to the rear ends of the chair arms, and hence the chair back as shown in Fig. 1 has a wider range of adjustment than it would have if connected up by means of the links or connecting arms 32 and 33 with the rear ends of the chair arms 27 and 28 as illustrated for instance in Fig. 2. When the back 25, arms

27 and 28 and foot rest frame 21 are all linked up together, any adjustment of the back 25 will result in a corresponding adjustment of the arms 27 and 28 and foot rest frame 21. For some purposes it is desirable to have the arms and foot rest connected to the back, and for other purposes it is more desirable to have the arms and foot rest disconnected from the back so that the back 10 may be adjusted over a wider range.

In order to provide for conveniently and reliably connecting and disconnecting the chair back to the chair arms I provide a horizontal shaft 34 journaled near opposite ends in the bracket members 26 of the chair back. The projecting ends of said shaft 34 are provided with collars 35 and 36 rigidly mounted on the shaft 34 and each provided with a segmental 20 projection 37. The collar 35 is provided with a hand wheel or hand grip 38 to enable the shaft 34 to be manually rotated through a portion of a revolution. Pivotally mounted upon the rear ends of the arms 27 25 and 28 are the arms or links 32 and 33, which when disconnected from the back 25 are held in an inclined position as shown in Fig. 1, by engagement with studs or stop pins 39 carried by the links 31. The arms 30 32 and 33 are thus prevented from falling into a substantially vertical position along side the links 31, and the free ends of arms 32 and 33 are held in position to be automatically engaged by cam ledges 40 carried 35 respectively by the brackets 26, which ledges constitute inclined guides to receive the forked free ends of the arms 32 and 33 and to guide them into position and engagement with the shaft 34 between the sides of the 40 bracket members 26 and the inner ends of the collars 35 and 36 so as to bring the segmental projections 41 carried by the arms 32 and 33 into position to be engaged by the 45 projections 37 to firmly lock the arms rotatably in engagement with the shaft 34 by partially rotating the shaft 34 so as to bring the projections 41 into a position between the shaft 34 and the projections 37 as shown in Fig. 3. A partial rotation of the shaft 50 34 in the opposite direction will serve to release the arms 32 and 33 from the shaft 34. When the arms 32 and 33 are locked to the back, the back 25 has a more limited range 55 of adjustment than when said arms 32 and 33 are disconnected from the back, and also any adjustment of the back results in a corresponding adjustment of the arms 27 and 28 and foot rest frame 21.

Hinged at 42 to the rear of the back 25 is 60 a depending rod 43 which passes over the face of an inclined projection 44 carried rigidly by the seat frame 17. A yoke shaped member 45 is pivotally attached at 46 to the projection 44 and tends by gravity to automatically clamp the rod 43 between the loop

portion of the yoke and the inclined face of the projection 44.

Thus the back may be raised to any desired height and the yoke 45 will automatically clamp upon the rod 43 to lock the back 70 to its adjusted position. To lower the back the handle 47 of the yoke 45 is lifted to release the rod 43, and allow the back to be lowered. When it is desired to hold the yoke 45 in its raised position a dog 48 pivotally attached to an ear 49 on the projection 44 is adjusted into position so that the nose 50 of the dog enters beneath the loop portion of the yoke 45 and holds the yoke 45 in raised position for any desired length of 80 time during which the back 25 may be freely moved up or down. The dog is adapted to be operated by hand or by the knee of the operator in either direction, thus leaving the hands free for other purposes. 85

The upper portion of the back is preferably provided with an indentation 52 which provides for a more extended range of adjustment for a head rest comprising a head rest stem or shank 53 adjustably supported in sleeves 54 and 55 projecting from the rear of the back, and in which the shank is adjustable endwise and also to a limited extent rotatably. Set screws 56 and 57 rigidly clamp the shank 53 in its adjusted 90 position. A segment 58 is pivotally connected to the upper end of the shank 53, and has a curved slot 59 through which a stud shaft projects from the shank 53 to receive a clamping nut 60 to lock the segment 58 100 to the shank 53. The segment 58 carries rigidly two upholstered head-rest pads 61 and 62, which are adjustable through a wide range to support the head of a patient in any desired position for examination and operation. A pair of shoulder stays 63 and 64 are mounted upon a forked shank 65 which slides in a groove 66 in the segment 105 58. The shank 65 is provided with a series of perforations 67 to register selectively with a perforation 68 in the segment 58. A pin having a stem to seat in the perforation 68 and an enlarged head 69 is adapted to also pass through any one of the perforations 67 to lock the shank 65 to the segment 58. The shoulder stays are adapted to be employed 110 to hold the shoulders of a patient in position. 115

A foot rest 22 is adjustably mounted upon the foot-rest frame 21. A socket 71 on the foot-rest is adapted to receive and adjustably hold the shank 72 of a supplemental foot-rest 73, which is designed to be adjusted up and down and clamped to any adjusted 120 position. Where children are to be operated upon the supplemental foot-rest is adapted to be adjusted into a horizontal plane with the upper face of the seat 18, or any lower 125 position as may be desired.

The apparatus herein illustrated and de- 130

scribed is capable of considerable modification without departing from the spirit of my invention.

What I claim is:

- 5 1. A surgical chair comprising a base a vertically and rotatably adjustable seat, a chair back having a medial recess at its upper end to receive and afford a wider range of adjustment for a head rest, a head 10 rest longitudinally and rotatably mounted relative to said back and adapted to enter said medial recess, and means to lock said back to any position of adjustment relative to said seat, said back being adjustable substantially 15 into a horizontal plane with the upper face of said seat.
2. A surgical chair comprising a base a vertically and rotatably adjustable seat, a chair back having a medial recess at its upper end to receive and afford a wider range of adjustment for a head rest, a head rest longitudinally and rotatably mounted relative to said back and adapted to enter said medial recess, means to lock said back 20 to any position of adjustment relative to said seat, and a vertically adjustable foot rest carried by said seat, said back and foot rest being adjustable substantially into a horizontal plane with the upper face of 25 said seat.
3. An operating chair comprising a chair seat, a chair back provided with a medial recess extending downwardly from the upper end of the chair back and through 30 from front to rear of the chair back, an adjustable member to be supported upon and relative to the chair back in substantially vertical alignment with said medial recess and adapted to enter said medial 35 recess, a supporting shank upon which said adjustable member is mounted, and means carried by said chair back to adjustably support said shank relative to the chair back.
4. An operating chair comprising a chair seat, and a chair back, said chair back being provided with a medial recess extending downwardly from the upper end of the chair back and through from front to rear 40 of the chair back, and affording a passage-way through which a head supporting member may project.
5. A surgical chair comprising a base, a seat mounted thereon chair arms at opposite sides of said seat each pivotally connected to said seat at each end to enable said arms to move endwise relative to said seat, a foot rest frame provided with a foot rest pivotally connected to said seat and to the forward ends of said arms to enable said arms 45 and foot rest to be adjusted in unison, a chair back pivotally supported relative to said seat and adjustable to different positions of inclination relative to said foot rest, means to detachably connect the chair back to the rear ends of said chair arms to enable said back to be adjusted either independently of said arms and foot rest, or in conjunction with said arms and foot rest, comprising links pivotally attached to the 50 rear ends of the chair arms at one end and forked and provided with laterally extending locking projections at their opposite ends, and a rotatable shaft carried by said chair back and provided with projections rotatable therewith to engage respectively with the forked end of said links and said laterally extended locking projections thereon to positively lock said links in pivotal relation with the shaft and rotatable projections 55 carried by said chair back.
6. A surgical chair comprising a base, a seat mounted thereon, chair arms at opposite sides of said seat, a chair back pivotally connected to said seat and adjustable from 60 a substantially vertical position to a position in substantially the same horizontal plane with the face of said seat, a locking bar pivotally attached to said chair back with one face in contact with a projection 65 carried rigidly relative to said chair seat, a gravity actuated yoke pivotally connected to said projection at opposite ends and with its middle portion in engagement with the opposite face of said locking bar to normally automatically engage and lock said locking bar to said projection, and a releasing member manually adjustable into and out of engagement with said yoke to support the weight of said yoke when desired 70 and hold said yoke out of locking engagement with said locking bar.

In testimony whereof I have affixed my signature.

EUGENE BERNINGHAUS.
